UNITED STATES PATENT OFFICE.

ALBERT B. CROWDER, OF ST. LOUIS, MISSOURI.

FUSIBLE LINK.

996,319.

Specification of Letters Patent. Patented June 27, 1911.

Application filed October 18, 1909. Serial No. 523,317.

To all whom it may concern:

Be it known that I, ALBERT B. CROWDER, a citizen of the United States of America, residing in the city of St. Louis, in the State of Missouri, have invented certain new and useful Improvements in Fusible Links, of which the following is a full, clear, and exact description, reference being had to the accompanying drawings, forming part of this specification.

My invention relates to a link of the description used in automatic sprinklers of fire extinguishing apparatuses or other devices wherein it is desirable to hold certain parts of the mechanism to which they are applied in assembled condition until sufficient heat has become present in the vicinity of the contrivance to cause the parts of the link to become separated by the fusing of a fusible binding substance uniting the members of the links.

An object of my invention is to provide a construction of the character named whereby the link members may be quickly and efficiently thrown apart in a lateral direction immediately after the fusible binding substance connecting them has become fused, thereby obviating the creeping action that is commonly present in links of this character and due to which the separation of the members is frequently interfered with as a consequence of the fusible binding substance between them becoming again hardened or set before separation of the members has taken place.

A further object of my invention is to so construct the link members that they will be restrained from longitudinal movement by the separating member by which they are thrown apart, and which restraint, while sufficient to relieve the fusible binding substance between the link members of very considerable strain to which it would otherwise be subjected, does not interfere with the separation of the link members when the fusible connection is destroyed.

Another object of my invention is to provide means incidental to the link members whereby they are separated to a specific degree in order that only the requisite amount of a fusible substance employed to connect the link members may be present between them.

Figure I is a perspective view of my link with the parts shown separated from each other. Fig. II is an edge view of the link

in condition for use. Fig. III is an edge view of the link with the parts shown in the separated positions they assume after the binding substance between them has been fused.

1, 1 designates two plates that constitute the main members of my link and in each of which is a transverse groove 2 that subdivides the plate into an outer section A 65 and an inner section B and is of segment shape in cross section. The plates are preferably provided with eyes 3 located in their outer sections A which receive the parts that are to be connected by the application of 70 the link thereto.

4 is a cylindrical rod or separating member that is adapted to occupy the grooves in the plates 1, which register with each other as seen in Fig. II, when said plates 75 are assembled. Between the plates is a layer 5 of fusible substance, such as solder.

It will be understood that when the layers of fusible substance become fused, under the action of heat, and the link plates are 80 moved in the opposite directions illustrated in Fig. III, each of the plates rides in contact with the separating member 4 and said member, by a positive rolling action, rides out of the grooves in the plates with the 85 result of throwing the plates apart, and the plates are therefore instantly separated upon the fusing of the binding substance previously connecting them; without any interval between the fusing and separating 90 actions, and as a consequence the objectionable creeping action hereinbefore referred to is obviated.

It will be observed on referring to the drawings that the inner section B of one 95 plate opposes the outer section A of the other plate. It will be further noted that the sections of each plate are offset from each other and in different planes, and that, as a consequence, the depth of one wall of 100 the groove is greater from the base of the groove 2 to the fusible substance receiving surface of the section A. The longer wall of the groove extending to the fusible substance receiving surface of the section B 105 terminates in a shoulder C providing a hook that is offset to a marked degree from the inner end of the section A at the opposite side of the groove and, therefore, when the link plates are assembled, as illustrated in 110 Fig. II, with the separating rod 4 between them in the grooves in the plates, the shoul-

ders C are so disposed that they extend beyond the axial line of the separating rod, the shoulders C of one plate extending past such axial line in one direction and the mating 5 shoulder of the other plate extending past the axial line of said rod in the opposite direction. As a result of this construction, the separating rod 4 is so disposed between the plates that it acts in a sense as a locking 10 member and serves to restrain the plates from longitudinal or endwise movements. The separating rod 4, in consequence of its function just mentioned, serves to relieve the fusible connection between the link 15 plates from much of the strain that would otherwise be exerted thereupon by the parts connected by the link, such as is incidental to the use of fusible links when assembled in conjunction with sprinkler heads of fire 20 extinguishing apparatuses. The links are, therefore, capable of withstanding much greater strain pending the fusing of the fusible binding connection between the link plates and the separation of such plates resulting 25 from the fusion of such connection.

It is highly desirable, and in fact, necessary, for the proper production of the fusible links in order that they will perform the best service, that the layers of fusible substance employed to connect the link plates be of sufficient thickness to properly unite the plates and hold them united during long continued use. In order that the proper 30 and predetermined amount of fusible substance may always be present between links manufactured in accordance with my improvement, I provide each link plate with

distance projections which protrude from the faces of the plates and are adapted to bear against plates arranged in opposition thereto. The distance projections are preferably arranged in pairs and preferably produced by indenting the plates from their outer surfaces, as seen at 7, Fig. I. The projections serve to distance the plates from each other, when they are laid together with fusible substance between them, in order that the layer of fusible substance may be only of the proper thickness.

I claim:

A link of the character described comprising a pair of plates, having registering segment shaped grooves extending transversely thereof intermediate of their ends and subdividing the plates into inner and outer 55 sections, a substantially cylindrical separating member occupying said grooves, and fusible substance connecting the outer section of one plate with the inner section of the other plate; the faces for receiving fusible substance of each section of said plates being in different planes relative to each other, and the depth from the plane of the inner fusible substance receiving face of each plate to the base of said grooves being 60 made greater than one half the diameter of said separating member, thereby providing hook-like portions for overlapping said separating member and for gripping the same at diametrically opposite points.

ALBERT B. CROWDER.

In the presence of—

E. B. LINN,
H. G. COOK.
